UNITED STATES PATENT OFFICE

FELIX TROYK, OF MORRIS, ILLINOIS

CARTON

Application filed September 15, 1931. Serial No. 562,891.

The present invention relates to cellular cartons, the interior of which is divided into cells or compartments by means of transverse and longitudinal partitions, and has for its object to improve cartons of this type.

One of the most common forms of cellular cartons is that in which a dozen eggs, arranged in two rows, are housed or packaged. Viewed in one of its aspects, the present invention may be said to have for its object to produce a simple and novel carton of this general type, composed of a single blank properly shaped, folded and glued.

In one of the most common forms of egg cartons the cross partitions are not only formed as integral parts of the body of the carton, but they are suspended at their upper ends from the upper portions of the front and rear walls, and upon setting up the cartons, these cross partitions are swung down so as to stand at right angles to the plane of the top of the carton. Viewed in one of its aspects, the present invention may be said to have for its object so to construct a carton of this kind that the center longitudinal partition, which cooperates with the cross partitions, is formed by folding the bottom wall which can be interlocked with the cross partitions only by being moved upward if the cross partitions have been swung down whereby, when the carton is set up, the cross walls are positively held against swinging out of their vertical positions as long as the longitudinal partition remains up.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a perspective view of one of my improved cartons, set up ready for use, the cover shown open; Fig. 2 is a central vertical

longitudinal section through the carton, with the cover closed, a section of the carton between the ends being omitted; Fig. 3 is an end view of the carton showing it, in full lines, squared up as the first step in the setting up operation, and showing in dotted lines an intermediate step in the folding of the body member to produce the bottom wall and longitudinal partition; Fig. 4 is a bottom plan view of the carton as it appears in Fig. 3, only one end of the carton being shown; Fig. 5 is an end view of a carton completely set up and illustrating a modified construction.

Referring to Figs. 1 to 4 of the drawings, it will be seen that my improved carton consists of a body member having front and rear walls 1 and 2, a bottom wall in the form of an inverted V and consisting of two sections 3 and 4 sloping downwardly toward the front and the rear, respectively, from the longitudinal center, together with a cover 5 and cross partitions 6. The cross partitions are connected by triangular pieces 7 to the upper edge of the front walls, and by suitable triangular pieces 8 to attaching strip 9 that is glued to the rear wall. Cooperating with the transverse partitions is longitudinal partition 10 rising from the apex or ridge in the bottom wall through the transverse partitions. This longitudinal partition is preferably formed by providing between the bottom wall sections 3 and 4 another section that is twice as wide as the height of the longitudinal partition; whereby, upon properly folding the blank, the bottom wall and the longitudinal partition in cross section resembles an inverted Y whose stem is of double thickness and extends far enough up to engage with the under side of the cover when the cover is closed. By this means, assuming that the longitudinal partition is held up, it serves as a support for the cover along the longitudinal center of same.

It is highly desirable that the cross parti-

tions be held securely against swinging out of their vertical position while the carton is in use, I therefore slot the longitudinal and the cross partitions in such a manner that 5 they can be inter-engaged only by moving the longitudinal partition up after the cross partitions have been swung into their upright positions. Then, by providing suitable co-operating shoulders between the longitudinal 10 and the cross partitions to prevent the longitudinal partition from moving downward after the carton had once been set up, there will be no danger of collapse of the carton or of partial disassembly in the use of the carton. 15 The slotting of the cross partitions involves simply the placing of two comparatively short slots 11 and 12, extending downwardly from the upper edge and downwardly from the lower edge, respectively, at the longitudinal center of the carton. The slotting of the two sections constituting the longitudinal partition is best shown in Figs. 2 and 4. Pairs of long, straight slits 14, 14 are cut transversely of the section 10 on opposite 20 sides of and at some distance from the central crease line 15 along which the section 10 is folded. Two curved slits 16, 16, with their concave sides directed toward the corresponding straight slits, are cut into the section 10 adjacent to each pair of straight slits. The two curved slits of each pair meet about at the juncture of the crease line 15 and a line forming a continuation of the corresponding straight slits; and each curved slit also meets 25 the corresponding straight slit between the ends of the latter. Slits are also cut in the section 10 parallel with the line 15 and extending from the ends of the straight slits nearest the line 15 to the corresponding curved slits. Other short, diagonal slits are cut 30 from the crease line to the curved slits, these short slits lying on the convex sides of the slits 16.

In this way groups of little windows are 45 formed in the section 10 and, when the latter is folded along the line 15, as shown in Fig. 2, it will be found to contain a series of vertical slots, extending through the top edge of the longitudinal partition formed thereby; 50 each slot having a flaring mouth 17 at the top, being pinched shut just below the mouth or entrance and then again widening as indicated at 18 and finally becoming again a mere slit, namely, the end of the slit 14. The material on one side of each slot forms a triangular nose or lug 19, one free edge of which constitutes one edge of the flaring mouth while the other free edge constitutes a horizontal, downwardly-facing shoulder extending 55 across the top of the wide part 18 of the slot.

The parts are so proportioned that the slots in the longitudinal partition register with the transverse partitions when the latter are swung 60 down; the slots 11 are about equal in depth

to the height of the noses or lugs 19; and the slots 12 are only about as deep as the distance between the lower ends of the slits 14 and the base of the longitudinal partition. The result is that when the carton is set up, as 70 shown in Figs. 1 and 2, the noses or lugs 19 engage in the slots 11 in the tops of the cross partitions and hold the longitudinal partition up; the slots 12 in the cross partition receive the base portion of the longitudinal partition; and a considerable portion of each cross partition is wedged into the lower end of the corresponding slit 14 below the window 18, thereby locking the transverse partitions 75 against swinging movements.

In setting up the carton the cross partitions must first be swung down into vertical positions and the longitudinal partition be then moved up through the same; and, obviously, separation of the longitudinal partition from the cross partitions can be effected only by a reverse relative movement, namely, a downward movement of the longitudinal partition. Therefore, by locking the longitudinal partition in its raised position, all accidental displacement of parts that would detract 80 from the efficiency of the carton is prevented.

The operation of setting up the carton is illustrated in Fig. 3 which shows the body of the carton opened up into a shell of about twice the height of the final product. After the cross partitions are swung down, as shown, the lower part of the shell is folded into the condition indicated in dotted lines in Fig. 3, the folding being then continued 90 until the condition illustrated in Fig. 1 is reached.

It will be seen that when the carton is set up, the double longitudinal partition presents practically a continuous upper edge to support the cover and thus makes the carton very strong in resisting vertical crushing stresses.

The angle at which the sections of the bottom wall slope may be varied as may the general design to change the shape of carton. Thus, in Fig. 5 I have illustrated a modification in which the sections 23, 24 and 30 corresponding to the sections 3, 4 and 10 in the other form, produce a comparatively shallow longitudinal partition and, with the front and rear walls, 21 and 22, form two deep troughs below and at opposite sides of the longitudinal partition. The cross partitions 26 are made more forked than are the partitions 6, in order to fill the valleys in the bottom of the carton, and the slots 12 are of course thereby brought closer to the top.

I claim:

A carton of the type described, comprising a single blank cut, scored and folded to form 125 a cover-locking strip, a cover, a rear wall, a rear bottom section, a rear longitudinal partition section, a front longitudinal partition section, a front bottom section, a front wall, cross partitions hinged to said front wall,
